US00D648939S

(12) **United States Design Patent**
Hoppus et al.

(10) **Patent No.:** **US D648,939 S**
(45) **Date of Patent:** **** Nov. 22, 2011**

(54) **BIN**

(75) Inventors: **Adam D. Hoppus**, Richfield, MN (US);
Jeffrey C. Carter, Minneapolis, MN (US)

(73) Assignee: **Target Brands, Inc.**, Minneapolis, MN (US)

(**) Term: **14 Years**

(21) Appl. No.: **29/356,374**

(22) Filed: **Feb. 24, 2010**

(51) LOC (9) Cl. **03-01**

(52) U.S. Cl. **D3/304**

(58) **Field of Classification Search** D3/200–201, D3/203.1, 203.3, 205–206, 273, 276, 304–315; D6/525, 475–476; D19/75–77, 86, 90, 92, D19/100; 206/203, 214–215, 822, 307.1; 229/100, 913–914, 406

(57) **CLAIM**

The ornamental design for a bin, as shown and described.

DESCRIPTION

FIG. 1 is a front, perspective view of a bin showing a first embodiment of our new design;

FIG. 2 is a front view thereof;

FIG. 3 is a rear view thereof;

FIG. 4 is a top view thereof;

FIG. 5 is a bottom view thereof; and,

FIG. 6 is a left side view thereof, the right side view being a mirror image of the left side view.

FIG. 7 is a front, perspective view of a bin showing a second embodiment of our new design;

FIG. 8 is a front view thereof;

FIG. 9 is a rear view thereof;

FIG. 10 is a top view thereof;

FIG. 11 is a bottom view thereof; and

FIG. 12 is a left side view thereof, the right side view being a mirror image of the left side view.

FIG. 13 is a front, perspective view of a bin showing a third embodiment of our new design;

FIG. 14 is a front view thereof;

FIG. 15 is a rear view thereof;

FIG. 16 is a top view thereof;

FIG. 17 is a bottom view thereof; and

FIG. 18 is a left side view thereof, the right side view being a mirror image of the left side view.

FIG. 19 is a front perspective view of a bin showing a fourth embodiment of our new design;

FIG. 20 is a front view thereof;

FIG. 21 is a rear view thereof;

FIG. 22 is a top view thereof;

FIG. 23 is a bottom view thereof; and,

FIG. 24 is a left side view thereof; the right side view being a mirror image of the left side view.

The features shown in broken lines depict environmental subject matter and form no part of the claimed design. The heavy dashed broken lines which define the bounds of the claimed design form no part thereof.
